UNITED STATES PATENT OFFICE.

ELIHU THOMSON, OF SWAMPSCOTT, MASSACHUSETTS, ASSIGNOR TO THOMSON ELECTRIC WELDING COMPANY, OF LYNN, MASSACHUSETTS, A CORPORATION OF MASSACHUSETTS.

ELECTRIC METAL-WORKING APPARATUS.

1,334,571.

Specification of Letters Patent. Patented Mar. 23, 1920.

Application filed August 28, 1918. Serial No. 251,758.

To all whom it may concern:

Be it known that I, ELIHU THOMSON, a citizen of the United States, and a resident of Swampscott, in the county of Essex and State of Massachusetts, have invented certain new and useful Improvements in Electric Metal-Working Apparatus, of which the following is a specification.

My invention relates to that class of electrical metal working apparatus in which heavy alternating or other rapidly varying electric currents are employed and in which, owing to the disposition of the leads conveying the current to and from the work or workholders, there is a free space between said leads which may become the locus of an intense magnetic field causing, by self-induction, a voltage drop in said leads.

My invention is particularly useful for apparatus in which an alternating current transformer supplies the heavy electric current to the clamps or holders through flexible leads permitting free movement of the workholders.

When the leads from the alternating current transformer for electric welding or similar uses are carried away from the transformer so as to leave a free space between such leads, there is a voltage drop depending upon the extent of this space and the length of the leads. This voltage drop is not wholly due to resistance but may be in fact largely inductive owing to the formation of a field between the connections to the work holder or work in which the magnetic density may rise to a high point. This would be largely obviated if the leads or conductors from the transformer ran nearly parallel and close together, but on account of the motion of the electrodes and other contingencies it is not always possible to so arrange them. The clamps or holders especially for electric welding, must have a play toward and from each other and it is also desirable to make as direct connections as possible to said holders from the active part of the welding transformer itself.

My present invention consists in means for overcoming the voltage drop due to the formation of such magnetic field and consists essentially in surrounding the locus of the field with a counter inductive circuit or shield so as to annul the contrary induction due to the production of the magnetic ef-

fects. This shield may be applied between the conductors and the locus of the field or may be applied at one or both sides of said conductors and in such manner as to in effect still surround or inclose said field.

In carrying out my invention the inductive circuit or shield would be preferably formed of copper and might take the form of a copper band and, when applied between the leads and the locus of the field, may nearly fill the space without, however, being in electrical connection with said leads or at least without electrical connection to at least one of them.

In the accompanying drawings:

Figure 1 is a general side elevation of an apparatus to which my invention is applied.

Fig. 2 illustrates diagrammatically the disposition of the leads above referred to where they run nearly parallel and close together between the transformer and the workholders.

Figs. 3 and 4 show in side view and section a modified arrangement embodying my invention.

Referring to Fig. 1, T indicates any form of alternating current transformer for welding or similar work with its iron core, massive secondary and primary coil related to the secondary as usual in this class of devices. F F indicates the flexible leads formed of bundles or laminæ of conducting material extending from the terminals of the massive secondary to the workholders or electrodes C C, which may be some distance from the transformer.

In the present illustration of my invention said leads are shown as flexible to permit movement of the electrodes or workholders to and from one another, but, as will be readily understood, the flexibility might be absent and other means provided for permitting a movement of the workholders or clamps, as well understood in the art.

With the transformer leads thus disposed there is a space between them which, during heavy work, becomes the locus of an intense magnetic field and causes an inductive drop which sometimes is serious, not only in demanding that the transformer be larger than it otherwise would need to be and also in reducing the power factor of the whole plant. As a means for remedying this condition, I

propose to apply a shield G of good conducting material, preferably a copper band closed on itself and practically surrounding said field. In the form of my invention 5 shown in Fig. 1, it may outline and nearly fill the space between the flexible leads, as shown. Said shield may be a hollow figure or closed electric circuit and its extent or depth may coincide with the depth of the 10 leads F F or may be greater or less than that depth. The shield may even be developed with turned-out edges to partly inclose the leads F F, all that is necessary being that they shall have a sufficient amount of copper 15 or good conducting material to inclose the space A fairly well. On the tendency to produce a powerful field in A by the welding currents at F F, which at any moment are in opposite direction, induced currents are 20 developed in the shield, which oppose the magnetism of the space A and reduce it to a low value. The shield might be made to conform closely to the leads and be made flexible so that it would move or collapse 25 more or less with the motion toward each other of the welding clamps; but this thoroughness of arrangement will be rarely necessary for annulling the major part of the effect. 30 Further modification and arrangements may of course be made, as for instance the shield may be a closed coil or wire wound up suitably or may be several closed circuits superposed, or in any way related to each other, provided they surround the space 35 which is magnetized by the heavy alternating currents and are adapted to form the seat of an induced current.

It will be evident that instead of a single 40 shield or a closed circuit G applied as shown in Fig. 1, I may employ a flat shield G' located directly in front of the conductors F F, when flexible, and having about the same figure as the shield G, but larger in breadth 45 and I may add, for more perfect results, a similar one back of the conductors F F.

This is shown in Figs. 3 and 4. Such a pair of shields in no wise interferes with the clamps C C or conductors F F, and if arranged close to F F, front and back, are almost as effective as the shield in the position Fig. 1. It will be seen that this shield does not occupy the space between the leads, but nevertheless surrounds the magnetic field and largely neutralizes it. 50

What I claim as my invention is:

1. In an electric metal working apparatus, the combination with the heavy current leads connected to the work and separated by a free space, of a counter inductive circuit or shield surrounding said space and separated from the leads as and for the purpose described. 60

2. In an electric metal working apparatus, provided with heavy current leads separated from one another by a free air space and connected to workholders movable to and from one another, of a counter inductive circuit or shield surrounding said space and adapted to allow free movement of said 70 workholders.

3. In an electric metal working apparatus, the combination with a transformer having leads connected directly to movable workholders and separated from one another by an air space, of a shield of good conducting material surrounding said air space. 75

4. In an electric metal working apparatus, the combination with a transformer having flexible leads connected directly to movable workholders and separated from one another by an air space, of a shield of good conducting material surrounding said air space but separated from the leads to allow freedom of movement thereof. 80

Signed at Lynn, in the county of Essex and State of Massachusetts, this 3d day of August, A. D. 1918.

ELIHU THOMSON.
